His Attorney.

UNITED STATES PATENT OFFICE.

WILLIAM C. WHITE, OF SCHENECTADY, NEW YORK, ASSIGNOR TO GENERAL ELECTRIC COMPANY, A CORPORATION OF NEW YORK.

RADIO-RECEIVING SYSTEM

1,365,576.

Specification of Letters Patent. Patented Jan. 11, 1921.

Application filed October 11, 1917. Serial No. 196,051.

To all whom it may concern:

Be it known that I, WILLIAM C. WHITE, a citizen of the United States, residing at Schenectady, in the county of Schenectady, 5 State of New York, have invented certain new and useful Improvements in Radio-Receiving Systems, of which the following is a specification.

My present invention relates to electron 10 discharge devices, and more particularly to the construction of such devices and their use in radio receiving systems.

Electron discharge devices of the type comprising a cathode adapted to be heated 15 to incandescence, a grid and an anode inclosed in an evacuated envelop, have been commonly employed in the past as detectors or receivers for radio signals in various ways. When these devices have been employed for the purpose mentioned it has been customary to use a battery for heating the filament and a second battery in a circuit between the cathode and anode for supplying current for operating the signal indicating 20 apparatus. With the construction of these devices which has generally been employed, it has been necessary to use a battery of twenty volts or more in the circuit between cathode and anode, which for convenience in 25 description may be designated as the plate circuit. It has also been frequently desirable to employ another battery in the circuit between cathode and grid for adjusting the normal potential of the grid to a value at 30 which the device will operate most satisfactorily.

The object of my invention is to provide a device which may be used as a radio detector or receiver, as well as for other purposes in 40 which a single battery of a few volts potential may be employed for fulfilling all of the functions carried out by the three batteries mentioned above. In carrying my invention into effect I construct the electron discharge device in such a way that the cathode and grid are separated by as small a distance as possible without danger of their actually touching each other, during the operation of the device and with the anode spaced 45 from the grid by a distance which may be slightly greater than the spacing between cathode and grid but which will in any case be very small. In using this device as a radio detector I connect the anode directly 50 to the positive terminal of the battery which

is employed for heating the filament and include in this circuit only an indicating means such as a telephone receiver. Any adjustment of the grid potential which it is necessary to make may be brought about by connecting the grid to the positive or negative terminal of the filament or to some point of an intermediate potential. In order that the device shall operate satisfactorily with the connection described, I find it preferable 60 that the metal of which the anode is composed shall be electro-positive with respect to the cathode.

The novel features which I believe to be characteristic of my invention are pointed 65 out with particularity in the appended claims. The invention itself, however, both as to its organization and method of operation, together with further objects and advantages thereof will best be understood by 70 reference to the following description taken in connection with the accompanying drawing in which:

Figure 1 is an elevation partly broken away 75 of a device which may be used in carrying my invention into effect: Figs. 2 and 3 are diagrams illustrating two different circuit connections which may be employed in radio receiving systems, and Fig. 4 is a characteristic curve of one of my devices showing 80 the relation between the voltage of the grid and the current in the plate circuit.

The device illustrated in Fig. 1 comprises an evacuated envelop 1, in which is inclosed a filamentary cathode 2, which is preferably of tungsten, a grid 3 which is in the form of a coil close to and surrounding the cathode and a cylindrical anode 4 close to and surrounding the grid 3. The anode 4 is preferably of a metal which is electro-positive with respect to cathode 2, and I have found in practice that nickel is especially suitable for the construction of the anode. Current for heating the filament may be supplied through the leading-in 90 wires 5 and leading-in wires 6 are connected to the ends of the grid coil 3. Leading-in conductor 7 provides a connection to the anode. The bulb 1 should be thoroughly baked out and exhausted to a vacuum as 95 good as that ordinarily employed with vacuum lamps. During exhaustion current should be passed through the device to heat the anode in order to expel any impurities or oxides which there may be at or near the 100 anode. The device should be exhausted to a vacuum as good as that ordinarily employed with 105 vacuum lamps. During exhaustion current should be passed through the device to heat the anode in order to expel any impurities or oxides which there may be at or near the 110 anode.

2

surface. This is of special importance as I have found that in order to obtain the most satisfactory operation the anode surface should be made as clean as possible. I find it convenient to make the grid 3 of tungsten and to use this as a cathode during exhaustion. By this expedient sufficient current may be passed through the device to heat the anode to the desired degree without any danger of injury to the cathode.

In Fig. 2 I have shown a circuit arrangement which may be employed with my device when used as an ordinary detector of radio signals. In this case the battery 8 which may be of about six volts, or even less, furnishes heating current for the cathode 2, variable resistance 9 being inserted in series with this battery in order to adjust the current through the cathode to the desired amount. The grid circuit of this device comprises the condenser 10, the usual inductance 11 and variable capacity 12 for tuning the circuit, the inductance 11 being coupled with the inductance 13 in circuit with the antenna 14. The anode 4 is connected to the positive terminal of battery 8 through the usual telephone receiver 15. In practice I also usually find it most convenient to bring the grid connection to the positive terminal of the cathode 2.

It has been demonstrated that the operation of a device of this sort with the circuit arrangement shown depends upon the gradual building up of a negative potential upon the grid by reason of the charging of the condenser 10 by successive radio frequency impulses received and the leakage of this charge during the interval between successive signals. In order for the device to operate most efficiently it is desirable that the normal grid potential should be such that a small variation in its potential will produce a large variation in the current between the cathode and anode. In practice this relation may conveniently be expressed in terms of milliamperes change in plate current per volt change in grid potential. In Fig. 4 I have shown a curve which represents this relation in one of my devices, which is constructed in the manner described. It will be seen from an inspection of this curve that when no signals are being received and the grid is therefore at substantially zero potential with respect to the cathode, the device will operate upon that portion of the curve which is practically straight and which is also substantially the steepest portion. The maximum degree of amplification will also be obtained when operating upon this portion of the curve. If the normal grid potential is positive the current taken by the grid will be much greater than when the grid is at zero potential or negative, and as a result the changes in grid potential produced by the signals will not be as great

as when the potential of the grid is zero or negative. It will therefore be evident that no extra battery is necessary in the grid circuit to adjust the device for most efficient operation. In order that the negative charge upon the grid which is accumulated thereon during the receipt of a signal may leak off after the signal has been received and before the succeeding signal is impressed upon the grid circuit, it is desirable to employ a high resistance 16 shunting the condenser 10.

I have also found that in the operation of such a device in the manner indicated in Fig. 2 there is a tendency for the grid to assume a negative potential with respect to the cathode when no signals are being received, especially if the grid is connected to the negative terminal of the filament. To avoid this it is usually desirable to connect the grid to the positive terminal of the filament as indicated in order that there may be at all times a slight leakage current between the grid and cathode.

By the use of a cathode of tungsten I am able to obtain an advantage over other forms of cathodes in that the cathode may safely be operated at a high enough temperature to give the electrons emitted an appreciable initial velocity. This initial velocity of the electrons will be great enough to cause a current flow between cathode and anode without any source of potential in the external circuit. By reason also of the fact that the material of the anode is electro-positive with respect to that of the cathode there will be a greater flow of current between the two than there would be if both were of the same material. There will also usually be a slight drop of potential through the resistance 9 and this drop of potential will cause the anode to be slightly positive with respect to the most positive end of the filament and thus assist the action of the device. It is evident of course that with the connection shown the anode is positive with respect to the negative end of the cathode by an amount equal to the potential of the battery 8.

In Fig. 3 I have indicated a modification of my invention which is adapted to receive continuous wave signals by the heterodyne method. In this case the plate circuit of the electron discharge device includes an inductance 17 which is coupled with the coil 11 in such a way that local oscillations will be produced which are of slightly different frequency from the received oscillations and which will combine with the received oscillations to produce beats in the telephone receiver 15. A variable condenser 18 is employed as a shunt to the telephone receiver 15 in order that the high frequency component of the current in the plate circuit may not be compelled to pass through the receiver. In order that a device of the type

described may be operated as an oscillator it is necessary that it should be adjusted to a point where it will act as an amplifier to such a degree that the energy which may be returned from the plate to the grid circuit is greater than the energy losses of the circuits, and previous devices of this type have required a separate source of potential in the plate circuit to bring them to a point where their energy amplification would be great enough to produce oscillations.

While I have illustrated and described the preferred embodiments of my invention it is by no means limited to the precise construction or circuit arrangement shown as many variations in the structural details as well as the manner in which it is used may be made without departing from the scope thereof as set forth in the appended claims.

What I claim as new and desire to secure by Letters Patent of the United States, is:

1. An electron discharge amplifying device comprising a metallic cathode adapted to be heated to incandescence, a grid and an anode inclosed in an evacuated receptacle, said anode being composed of a metal which is electro-positive with respect to the metal of the cathode and the parts being so proportioned and so close to each other that the maximum degree of amplification of which the device is capable may be ob-

tained with the grid normally at substantially zero potential with respect to the cathode and with a single source of energy 35 of a potential as low as six volts for supplying current for heating the cathode and for the operation of the device as an amplifier.

2. The combination in a radio receiving 40 system of an electron discharge device having a filamentary cathode of tungsten, a grid and an anode of nickel inclosed in an evacuated envelop, a single battery of not over six volts for supplying current for heating 45 the cathode and for operating signal indicating means, the two terminals of said battery being connected to the terminals of said cathode, means for impressing received signals upon said grid and a connection 50 from the anode to the positive terminal of said battery, said connection including signal indicating means.

3. An electron discharge device comprising a filamentary cathode of tungsten, a 55 grid and a nickel anode inclosed in an evacuated receptacle, the parts being so proportioned and so close to one another that the device is capable of operating to produce oscillations from a direct current source 60 of a potential as low as six volts.

In witness whereof, I have hereunto set my hand, this 10th day of October, 1917.

WILLIAM C. WHITE.
